UNITED STATES PATENT OFFICE

169,840

HEATER

Edward A. Farr, Columbus, Ind., assignor to
Arvin Industries, Inc., Columbus, Ind., a cor-
poration of Indiana

Application September 6, 1952, Serial No. 21,370

Term of patent 7 years

(Cl. D81—10)

To all whom it may concern:

Be it known that I, Edward A. Farr, a citizen of the United States, residing at Columbus, Indiana, have invented a new, original, and ornamental Design for a Heater, of which the following is a specification, reference being had to the accompanying drawings, forming a part hereof.

Fig. 1 is a front elevation of a heater embodying my new design;

Fig. 2 is a side elevation of the heater; and

Fig. 3 is a rear elevation of the heater.

The side not shown in the drawings is substantially like the side shown in Fig. 2.

I claim:

The ornamental design for a heater, as shown and described.

EDWARD A. FARR.
